UNITED STATES PATENT OFFICE.

ALFRED M. CHAFFEE, OF OXFORD, MASSACHUSETTS.

CONSTRUCTION OF CLOTH-BOARDS.

1,100,354.

Specification of Letters Patent. Patented June 16, 1914.

Application filed May 5, 1913. Serial No. 765,443.

To all whom it may concern:

Be it known that I, ALFRED M. CHAFFEE, a citizen of the United States, residing at Oxford, in the county of Worcester and

5 State of Massachusetts, have invented a new and useful Construction of Cloth-Boards, of which the following is a specification, reference being made therein to the accompanying drawings.

10 This invention relates to an improved construction for cloth-boards or winding-boards such as are employed for winding piece-goods, silks, woolens, felts and other similar cloth or fabrics; the object of my invention being to provide a stronger, more efficient, and non-warpable construction that can be manufactured with economy and practical facility.

To this end my invention consists in producing a cloth-board in which the longitudinal side bars of the frame are made from thin sheet-metal or the like, formed hollow with a U-shaped or approximately semi-cylindrical cross-section, in combination with 25 transverse members having rounded ends that fit within the hollow of the side-bars and support the same; the whole being rigidly secured together and a smooth even surfaced exterior produced thereon, by a 30 covering of one or more plies of suitable paper fabric.

This novel construction is more fully explained in the following detailed description; the particular subject matter claimed 35 being hereinafter definitely specified.

In the drawings, Figure 1 represents a perspective view of a complete cloth-board. Fig. 2 is a plan view of the frame without the exterior covering. Fig. 3 represents, on 40 somewhat larger scale, the cross-section at line X X, of one of the side-bars. Fig. 4 is a cross-section at line Y Y, showing the frame-connecting joint and a portion of the external covering. Fig. 5 shows, by side 45 and plan, the shape of the ends of the cross-pieces as prepared for assembling in the frame. Fig. 6 is an enlarged cross-section-form of the side-bar, similar to Fig. 3 at line X X, and Fig. 7 is a like section illustrating a modified edge form.

In referring to the drawings, the numeral 12 indicates the longitudinal members or side-bars of the frame; 13 the transverse members or cross-pieces, located at the ends 50 of the board; and when required at one or more intermediate positions in the length

thereof; and 15 indicates the incasing sheet forming the exterior contour and surface of the completed cloth-board.

In constructing a cloth-board according to 60 my invention, the side-bars or longitudinal members 12 of the frame are each formed of a strip of thin sheet-metal bent transversely to a U-shape, or to have an approximately semi-cylindrical hollow cross-section, 65 as at 2, and with edge portions 4 that extend somewhat beyond the half circular portion, as best shown in Figs. 3, 6 and 7. In its longitudinal direction the bar is made straight with the same cross section throughout. The 70 extended portions 4 are best slightly inclined inward or toward each other, so that the distance between them from one to the other is somewhat less than the diameter of the cylindrical portion; and preferably the extreme 75 edges are slightly curved outward, as at 5 on Fig. 6. If desired the extended edge portions 4 can be made transversely parallel with each other, as in Fig. 7; or in other instances formed with or without the inwardly set lip 7 thereon.

The cross-pieces 13, which as shown are made of wood, are formed with rounded ends 80 to fit the interior hollow of the semi-cylindrical metal bars, and are reduced across 85 their top and bottom faces, as at 8, to receive the extended edge portions 4 of the side-bars 12, so that the faces 9 of the cross-piece will be approximately flush with the external diameter of the semi-cylindrical metal 90 side-bars, while the edges of the metal are a little below the flush alinement. These frame members 12 and 13 are assembled by inserting the rounded heads 3 of the cross-pieces between the opposite edges 4 of the 95 hollow metal side-bars, and against the interior of the cylindrical portion 2; the metal by its springing capacity yielding sufficiently for the entrance thereof, and then resiliently closing in against the oppositely reduced 100 faces 8 with a firm grip thereon; thus giving a readily assembled strong connection without requiring any nailing of the joints, while the ends support the sheet metal side-bars from the interior, and maintain the 105 cross-sectional contour thereof at the ends and at any desired intermediate stations; thus preventing any liability of crushing in the edges of the clothboard laterally. This frame when assembled is coated with glue 110 and inclosed in a casing of paper or like fabric 15, wound about it in one or more

plies; the plies being smoothly laid thereon and upon each other, and united together throughout their adjacent surfaces by glue or other adhesive substance, as heretofore employed; and said paper is best shrunk in position.

As I have heretofore, in practice, long employed the idea of covering cloth-winding boards with plies of paper shrunken thereon, it will be understood that I do not herein broadly claim that feature *per se* as of my present invention.

What I claim as of my invention and desire to secure by Letters Patent is—

- 15 1. A cloth-board construction including a frame consisting of a pair of longitudinally straight hollow side-bars made of sheet-metal of approximately uniform U-shaped cross-section, said side-bars oppositely disposed with their open sides toward each other; in combination with a plurality of rectangular wooden crosspieces having their ends respectively shaped to correspond with the interior cross-section and interlockingly 20 engaged within said hollow sheet-metal side-bars, connecting and supporting the same, and maintaining the cross-section contour 25 thereof, substantially as set forth.
2. A cloth-board embodying the construction set forth, consisting of longitudinal side-bars made of thin sheet-metal formed of approximately semi-cylindrical cross-section

shape, with extended inwardly inclined edges; in combination with crosspieces having rounded ends and reduced faces fitting the semi-cylindrical hollow interior of said sheet-metal side-bars, and between said inwardly inclined edges, and an exterior casing of paper fabric wound about and adhesively united therewith in a smooth unbroken surface.

3. A cloth-winding board comprising longitudinal side-bars made of sheet-metal and having a cross-sectional shape consisting of a semi-cylindrical main portion with oppositely resilient edge portions that slightly incline inward and then curve outward; in combination with end members or crosspieces of a thickness equal to the diameter of the semi-cylindrical side-bar, said crosspieces having rounded ends and reduced faces adapted for transverse insertion within said hollow sheet-metal side-bars, and interlocking between the inwardly inclined edge portions thereof, and an external surface covering, of shrinkable fabric securing said parts together.

Witness my hand this 28th day of April, 1913.

ALFRED M. CHAFFEE.
